(57) **CLAIM**

The ornamental design for a plasma gun anode, as shown and described.

DESCRIPTION

FIG. 1 is a perspective view of a first embodiment thereof;

FIG. 2 is a front view of the first embodiment thereof;

FIG. 3 is a rear view the first embodiment thereof;

FIG. 4 is a side view the first embodiment thereof;

FIG. 5 is a perspective view of the first embodiment thereof, showing for illustrative purposes only, the anode of FIG. 1 mounted in the nozzle assembly of a plasma gun;

FIG. 6 is a perspective view of a second embodiment thereof;

FIG. 7 is a side view of the second embodiment thereof;

FIG. 8 is a perspective view of a third embodiment thereof; and,

FIG. 9 is a side view of the third embodiment thereof.

Broken lines shown in the figures are for illustrative purposes only and form no part of the claimed design.
